UNITED STATES PATENT OFFICE

117,493

DESIGN FOR AN AUTOMOBILE

Edgard C. De Smet, Toledo, Ohio, assignor to Willys-Overland Motors, Inc., Toledo, Ohio, a corporation of Delaware

Application August 19, 1939, Serial No. 86,785

Term of patent 3½ years

To all whom it may concern:

Be it known that I, Edgard C. De Smet, a citizen of the United States, residing at 2040 Upton Ave., Toledo, county of Lucas, and State of Ohio, have invented a new, original, and ornamental Design for Automobiles, of which the following is a specification, reference being had to the accompanying drawings, forming part thereof.

In the drawings,

The dominant features of my automobile design are shown in solid black lines in the drawings.

I claim:

The ornamental design for an automobile, substantially as shown and described.

EDGARD C. DE SMET.
